UNITED STATES PATENT OFFICE.

JULIUS H. GIMPEL, OF DECATUR, ILLINOIS.

BRAKE-BEAM SAFETY HANGER.

Application filed June 26, 1925. Serial No. 39,640.

This invention relates to safety hangers for brake beams for railway cars and the like.

The principal object of the invention is the provision of new and improved means for supporting the brake beam and brake mechanism and preventing their falling beneath the wheels of the car in case their supports become broken or accidentally detached.

Another object of the invention is the provision of new and improved means for attaching the safety hangers to their supports, whereby the same may be readily detached or removed and replaced when it becomes desirable or necessary.

Another object of the invention is the provision of new and improved supporting means for the safety hanger bars.

Another object of the invention is the provision of a new and improved brake beam safety hanger that is simple in construction, cheap to manufacture, easily assembled, may be readily attached to the truck, efficient in operation, and that is not likely to become broken or get out of order.

Other and further objects and advantages of the invention will appear from the following description taken in connection with the accompanying drawings, in which—

Fig. 1 is a vertical section through a railway truck showing the invention in position thereon, with parts removed;

Fig. 2 is a plan view of the attachment; Fig. 3 is a section on line 3—3 of Fig. 2; and

Fig. 4 is a section on line 4—4 of Fig. 2.

In railway equipment the greater portion of the brake mechanism is carried by the trucks. The brake beams are suspended from the truck frames by suitable hangers. These hangers are placed under severe strain when the brakes are applied because of the friction between the contacting surfaces and the force exerted by the rotating wheels.

Furthermore there is considerable strain on the brake hangers even when they are released because the brake beams, shoes, etc., which they support, usually weigh from 3500 to 4000 pounds. As a result of these conditions it is not unusual for the brake hangers to become broken or detached from the trucks at one or both ends, thus permitting

the brake beam to fall, and unless means are provided for supporting it the beam may cause a wreck or seriously injure the car.

Numerous devices have been provided for supporting the beam in case the hanger breaks or becomes accidentally disengaged, but most of these devices are costly, cumbersome, and are extremely difficult to attach to the truck.

In the present invention the parts are readily assembled, and are easily attached to the trucks.

On the drawing the reference character 10 designates a portion of a truck having a side frame 11 of any approved construction. The brake beams 12 having the brake shoes 13 thereon are supported from the frame by the links or hangers 14 in the usual manner. The truck is also provided with the usual spring plank 15 which in the present instance is shown as being a channel bar. Since the truck frame, brake beam, hangers, shoes and spring plank constitute no part of the present invention it is not thought necessary to further describe the same.

One or more safety supporting bars 16, two being shown, are suspended beneath the brake beams for supporting the same in case the links or hangers 14 should break or become disengaged from the truck frame. Suitable means are provided for supporting the bars 16 from the spring plank 15. As shown, a plurality of hangers is provided for each bar. Each hanger 17 is provided with a return bend 18 forming an open slot 19 which is adapted to engage one of the flanges 21 of the spring plank 15. The hangers 17 and the flanges 21 may be and preferably are provided with aligned apertures through which a pin 22 may be inserted for preventing disengagement or displacement of the hangers 17 along the spring plank. Each of these pins 22 is provided with means such as the cotter pins 23 for preventing their withdrawal.

The lower end of each of the hangers is provided with means for interlocking with the bar 16. Any suitable means may be provided for this purpose. As shown, the lower end of each hanger is provided with a T-shaped slot 24 and the bar 16 may be of corresponding shape for slidably engaging the slots in the hangers 17 at each side

of the spring plank 15. The parts are so arranged that the bars 16 are adapted to engage the bottom of the spring plank 15 for preventing vertical movement and the consequent disengagement of the hangers from the flanges of said plank.

Suitable means are provided for holding the bar 16 in fixed position relative to the hangers when the parts have been assembled.

10 Any suitable means, such as the pins 25, may be employed. These pins extend through alined openings in the bar 16 and the lower portion of the hangers 17. Cotter pins or other securing means 26 prevent the accidental withdrawal of the pins 25.

In assembling the device the hangers 17 are attached to the flanges 21 of the spring plank 15 so that their slots will be in alignment, after which the bars 16 are slid into the slots to the proper position, and the parts secured in position by the pins 22 and 25.

The bars 16 extend longitudinally of the truck and are of such a length that they will overlap the wheels whereby the truck beam will be supported by the bar 16 should the hanger 14 become broken or displaced. The bars are extended in both directions past the periphery of the wheel in order that it will be impossible for the brake beams to become disengaged from said bars.

While the interlocking connection between the hangers and the bar 16 is shown as being formed of a T-shaped slot and correspondingly shaped bar, it is understood that this interlocking connection may be of any form so long as the bar may be slid to position and interlock with the hanger. By means of this arrangement the weight supported by the bars 16 will be carried directly by the shoulders on the hangers formed by the slots, the pins 25 supporting none of the weight and being used merely to prevent the movement of the bars 16 along the hangers.

45 It is thought from the foregoing taken in connection with the accompanying drawings that the construction and operation of my device will be apparent to those skilled in the art, and that various changes in size, shape, proportion and details of construction

may be made without departing from the spirit and scope of the appended claims.

I claim as my invention:

1. A safety support for brakke mechanism, comprising a plurality of hook members having a T-shaped channel in the lower portion of each of said members, a rigid bar having a T-shaped upper portion slidably mounted in said channel for forming an interlocking connection between said hook members and said bar, and means extending transversely through said bar and members for securing said bar to said members.

2. In combination, a truck comprising axles, a frame for connecting said axles, said frame including a channel member arranged transversely of said truck, brake mechanism suspended from said frame, a pair of supporting bars having T-shaped upper portions, means for suspending said supporting bars from said frame beneath said mechanism, said means comprising hangers having hooks engaging the flanges of said channel member, the hangers at each side of said truck being provided with alined T-shaped slots adjacent to the lower portion of said channel member for receiving and supporting said supporting bars, said supporting bars being adapted to engage said channel member for preventing vertical movement of said hooks, means for preventing movement of said hooks along said channel member, and means for preventing longitudinal movement of said bars relative to said hooks.

3. An attachment for supporting railway brake beams in emergencies, comprising a pair of hangers having open slots in their upper ends for engaging a flange and provided with alined apertures for receiving a bolt for securing said slotted end to said flange, the lower end of said hangers being provided with alined T-shaped slots, a bar slidably mounted in said slots, and means for rigidly securing said bar to said hangers, for supporting said bar adjacent to the open ends of said slots.

In testimony whereof I affix my signature.

JULIUS H. GIMPEL.
